UNITED STATES PATENT OFFICE.

WILLIAM ERASTUS WILLIAMS, OF WILMETTE, ILLINOIS, ASSIGNOR, BY MESNE ASSIGNMENTS, TO STEEL WHEEL CORPORATION, OF LANSING, MICHIGAN, A CORPORATION OF MICHIGAN.

CONCAVE DEMOUNTABLE-RIM DISK WHEEL.

Application filed March 9, 1923. Serial No. 623,887.

The object of my invention is to produce a very simple disk wheel decreasing the amount of material, while increasing strength and securing the best service of which a disk wheel is capable, together with other detailed merits herein set forth.

Reference will be had to the accompanying drawings of which Figure 1 is a front elevation of my wheel. Figure 2 is a side sectional elevation on line 2—2 of Figure 1. Figure 3 is a section on line 3—3 of Figure 1. Figure 4 is a section on line 4—4 of Figure 1. Figure 5 is a front elevation of a portion of the rim of the wheel and disk when used with a split rim. Figure 6 is a top plan view looking at the edge of the rim in the direction of the arrow *a*, Figure 5. Figure 7 is a section on line 7—7 of Figure 5. Figure 8 is a radial section through the valve stem. Figure 9 is a section on line 9—9 of Figure 5. Figure 10 is a section of the rim and margin of the disk on line 10—10 of Figure 5. Figure 11 is a section through the rim and margin of a disk showing a modified form. Figure 12 is another section through the rim and margin of a disk showing another modified form. Figure 13 is another section through the rim and margin of a disk showing a further modified form.

Figures 1 to 4 inclusive show the construction of my disk as applied to what is known as a quick detachable pneumatic tire rim, a type of rim which has the main rim portion a continuous solid ring.

Figures 5 to 13 inclusive show the adaptation of my invention for use with what is known as a split rim.

Rims of the quick detachable type are those in which a ring or portion of the rim is removed in a tire change, but with a split rim the rim is usually made in one piece and is cut asunder or not united as a continuous ring, but is spliced by a detachable splice and in making a tire change with a split rim the rim is collapsed inward by having its ends pushed past each other after the connection splice is disengaged and thus the rim made smaller by contraction and the tire removed from the outside.

The terms inwardly and outwardly used herein indicate to and from the wheel axis and the term forward indicates from the car body, and rearward toward the car body.

In the drawing, 1 indicates the hub of an automobile wheel here shown as the rear wheel. 2 indicates the main portion of a quick detachable rim and 3 indicates the side ring or detachable flange of the quick detachable rim. 4 indicates an ordinary brake drum and 5 indicates the integral flange of the hub 1.

I prefer to make the web of my wheel of a concave disk shape as is indicated by 6 and this disk is reinforced for a region around the hub by reinforcing disk 7, and these two disks are spaced apart at the hub region and secured to the hub by means of a series of stud bolts 8.

The concave portion of the disk extends outward into contact with the rim 2 at the point 9, and from this point 9 the disk is turned forward somewhat upon itself into the flange 10. This flange 10 abuts the inclined portion 11 of the quick detachable rim 2 and the rim is seated on the flange portion 10 and the seat portion 9 of the disk 6 and is held in place against lateral displacement by the clamping member 12. The normal section of this clamping member, here shown as a ring 12, is shown in Figure 4. Other sections adapted to the securing in place of particular types of rims are indicated at 12^a in Figs. 7, 8 and 10, at 12^b in Fig. 9, at 12^c in Fig. 11 and at 12^d in Fig. 13. A series of bolts 13 having their nuts 14 seated on bosses 15 of the ring 12, pass through the ring and through the disk and have their heads 16 seated in slight depressions in the back of disk 6 and thus clamp the ring 12 in place, holding the rim securely on to the margin of the disk.

For purposes of what is called outside inflation a portion of the disk at 16' is indented where the air valve passes through (see Figs. 1 and 3) and thus the air valve may be reached from the front face of the wheel. The ring 12 is also pierced for the entrance of this air valve 17, the latter being shown in dotted lines.

The split rim shown in Figures 5 to 9 inclusive and indicated by 18, is spliced by means of a splice plate 19, having edges 20 turned over on all four sides, and these edges 20 embrace the sides and ends of a pair of blocks 21, which are permanently secured by rivets 22 to the ends of the rim ring 18. The

splice plate is secured firmly to both ends of the rim by the cap screws 23 screwed through the blocks 21 and into the metal of the rim

18. The blocks 21 are virtually a part of the rim 18 when riveted in place, and the embracing action of the plate edges 20 effectively prevents lateral as well as circumferential relative displacement, thus rendering the blocks and rim ends practically unitary.

19. The rim is shown as provided with an integral inwardly extending portion or rib, for cooperation with the disk flange in fastening the rim on the disk. This rib or inwardly extending portion of the rib may 20 be constituted of the rim-trough or gutter 11 of Figs. 1 to 4 or the supplemental rib 24 of Figs. 5 to 12, or the depressed rib 25 of Fig. 13. In each case the inclined or oblique rear side of the rib-like portion 21 acts with the peripheral flange 10 of the disk to hold the rim securely under the clamping action of the ring or flange 12. The disk periphery, while turned forwardly and inwardly in all cases as shown at 9 and 25, in Figs. 11, 12 and 13 it is further extended forwardly to provide the substantially axial prolongation 26, the angles being slightly less prominent in Fig. 13 as indicated at 10^a and 26^a.

30. The clamping ring or flange 12 serves in all cases to press the rim rearwardly against the flange 10 of the disk. In Figs. 1 to 11 and 13 the clamping ring contacts directly the rib of the rim, whereas in Fig. 12 it contacts the rim in front of the rib, the functioning being the same.

35. The point is to carry the rim on the disk on the forward curved portion of the disk, as represented by the portions or flanges 9, 10 and 26, and to clamp against these portions or flanges the rib-like inward projections 11, 24 or 25. By this outwardly and forwardly curved form of the disk I am able to use slightly less metal in the disk 40 and yet provide for what is called outside inflation for the air stem of the pneumatic tire.

45. In using a split rim on a narrow contact line, as I have indicated, it is desirable that the rim should be quite securely fastened at the splice and this splice plate 19 with its side flanges 20, embracing on four sides the blocks 21, holds the split ends of the rim in alignment independently of the screws 23, which is a great desideratum.

50. The forwardly curved flange on the margin of the disk results in making a stronger marginal flange on a concave wheel than is obtained by reverse bending of the metal of the margin of the disk. It is quite a stress 55 upon the metal to bend it rearwardly enough to permit outside inflation and then forwardly for rim contact and then make a reverse rearward turn on the margin for producing a flange for supporting the rim

and thus the flange turned inwardly and forwardly on the margin of my concave disk is an important feature.

55. The depression 25 in the rim 18 serves the same purpose as the projection 24 and that 70 permits the rim 18 to be made out of flat stock metal instead of a special rolled section that is required with the projection 24, which is a great desideratum since many steel mills are equipped to make flat stock 75 strips while special sections are special work with the less number of opportunities for purchase of the material.

80. The clamping or splice plate 19 furnishes a secure fastening for the split rim ends 85 against displacement in every direction, due to the overturned edges of the plate embracing on all sides the blocks 21 which are permanently secured to the split ends of the rim 18.

85. The clamping ring 12 may be shaped in any suitable form and instead of having the bolts 13 horizontally arranged I may arrange the bolts in a diagonal position as indicated by dotted lines of the bolt 30 in Fig. 10. 90 This inclined position of the bolt 30 makes unnecessary as deep a depression in the ring as indicated by 31 for a seat for the bolt 13, see Figure 7.

95. In place of the ring 12 I may use clips of any suitable form at the location of the bolt, depending on the wish of the user of the wheels.

100. The arrangement of the disk connection to the rim is such that it amounts to substantially a line or limited surface contact and since that is the case the clamping means will always obtain a good fit between the rim and the disk, whereas in other cases where the rim is intended to fit at two or 105 more zones of circumferences an exact fit of these two zones is not easily obtained and there results a slight movement at some points causing a squeak of the parts, but with the contact as I have provided this 110 fault is overcome.

115. What I claim is:

120. 1. In a device of the class described, a concave disk forming the web of the wheel having a marginal flange turned inwardly and forwardly and furnishing a seat for a demountable rim, said rim being provided with an inwardly extending portion arranged to seat on the marginal flange of the disk and adapted for holding the rim against lateral displacement, in combination with means for clamping laterally the margin of the disk and the inward projecting portion of the rim.

125. 2. In a device of the class described a forwardly concave disk having a marginal flange turned laterally forward and radially inward for furnishing a demountable rim seat, a demountable rim having an interior rib portion seated on the said seat in combi-

nation with means for clamping in lateral direction the inward extending portion of the rim to the margin of the disk.

3. In a device of the class described a split 5 demountable rim having a splice plate connecting the split ends of the rim, a disk forming the web of the wheel and provided with a marginal flange upon which the said rim is seated, said marginal flange being indented to accommodate the said splice plate and to provide circumferential abutments for the plate ends.

4. In a device of the class described, a disk forming the web of the wheel concaved on 15 its outward face and having a marginal flange bent laterally forward and then radially inward to furnish a seat for a rim.

5. In a device of the class described, a disk forming the web of the wheel and having 20 an inwardly and forwardly turned flange on its margin adapted to form a demountable rim seat, and a rim having an inwardly projecting portion adapted to abut the said inwardly and outwardly turned flange.

25 6. In a device of the class described, a disk forming the web of the wheel and provided with an inwardly and forwardly turned marginal flange adapted to furnish the seat for a demountable rim; a tire-carrying rim mounted on the said marginal flange and provided with an inwardly extending rib adapted to abut in lateral direction against 30 said inwardly and forwardly turned marginal flange of the disk and means for clamping the parts together.

7. In a device of the class described, a disk having a marginal flange turned forward from the body of the disk and turned over on its edge in a diameter smaller than the 35 largest diameter of the disk and adapted to carry thereon a demountable rim, a demountable rim seated on the margin of the

said disk and provided with an inwardly projecting portion adapted to abut laterally against the disk margin and clamping means 45 for clamping the said rim laterally to the margin of the said disk.

8. In a device of the class described, a disk forming the web of the wheel and having a flange turned on its margin forwardly from 50 the body of the disk and of smaller diameter than the largest diameter of the disk; on a demountable rim seated on the marginal flange of the said disk through the medium of a portion of the said rim being depressed 55 inwardly to form a projection of smaller diameter than the main tire seat of the rim and means for clamping the rim and disk together.

9. In a device of the class described, a disk forming the web of a wheel and having a 60 forwardly turned flange of smaller diameter than the largest diameter of the disk and adapted to seat a demountable rim on the said flange; a demountable rim having a portion of the tire carrying base of the said 65 rim pressed inwardly to form an inward annular projection of smaller diameter than the main tire base seat and adapted to furnish a lateral bearing against the margin of the disk and means for clamping the parts 70 together.

10. In a device of the class described, a disk forming the web of the wheel, a split demountable rim adapted to be carried on said margin of the said disk in line contact and 75 provided with a substantial splice across the split of the rim ends; said splice adapted to hold the split ends of the rim from displacement in any direction, and the margin of the said disk depressed to accommodate the splicing member of the said rim and to form a 80 circumferential abutment therefor.

WILLIAM ERASTUS WILLIAMS.
